UNITED STATES PATENT OFFICE.

HARRY E. HEATH, OF LYNN, MASSACHUSETTS, ASSIGNOR TO GENERAL ELECTRIC COMPANY, A CORPORATION OF NEW YORK.

THERMO-ELECTRIC COUPLE.

No. 824,015.

Specification of Letters Patent.

Patented June 19, 1906.

Application filed August 7, 1905. Serial No. 273,216.

To all whom it may concern:

Be it known that I, HARRY E. HEATH, a citizen of the United States, residing at Lynn, county of Essex, and State of Massachusetts, have invented certain new and useful Improvements in Thermo-Electric Couples, of which the following is a specification.

My present invention relates to a combination of different materials for use as a thermo-electric couple. This couple comprises as one of its elements a member made of silicon, preferably cast into the desired shape. The silicon member may be in the form of a rod, sheet, or bar, and associated with this bar to form the other member of the couple I use one of a number of suitable metals—such, for example, as copper, nickel, or the like. The joints between the two members may be made, for example, by casting the nickel or other metal about one end of the silicon rod, or, if desired, the nickel or copper in the form of wire may be wound tightly about one end of the silicon rod. As many couples of this

character as may be desired may be used in series with each other or in any other connection understood by electrical engineers.

The couple which I have described possesses the important advantage of high electromotive force. With a rise in temperature of about 600° centigrade the electromotive force of the couple amounts to about .25 of a volt. The silicon, moreover, is a highly heat-refractory material and may to advantage be submitted to high temperatures.

What I claim as new, and desire to secure by Letters Patent of the United States, is—

1. A thermo-electric couple one member of which is constructed of a body of silicon.
2. A thermo-electric couple one member of which is constructed of a body of cast silicon.

In witness whereof I have hereunto set my hand this 4th day of August, 1905.

HARRY E. HEATH.

Witnesses:

JOHN A. McMANUS, Jr.,
HENRY O. WESTENDARP.
